UNITED STATES PATENT OFFICE.

OSCAR HAMMERSTEIN, OF NEW YORK, N. Y.

BATH-TUB AND WASH-BASIN.

SPECIFICATION forming part of Letters Patent No. 360,292, dated March 29, 1887.

Application filed December 24, 1886. Serial No. 222,505. (No model.)

To all whom it may concern:

Be it known that I, OSCAR HAMMERSTEIN, a resident of New York city, in the county and State of New York, have invented an Improved Combined Bath-Tub and Wash-Basin, of which the following is a full, clear, and exact description, reference being made to the accompanying drawings.

My invention relates to a combined bath-tub and wash-basin; and it consists in having a cover for the tub, said hinged cover having a wash-basin therein, and means for supplying said basin with water, as will be more fully hereinafter set forth.

15 In the accompanying drawings, Figure 1 is a plan view of my invention. Fig. 2 is a vertical section on the line *c c*, Fig. 1. Fig. 3 is a vertical section on the line *k k*, Fig. 1. Fig. 4 is a perspective view of a modification.

20 A is the bath-tub, which is supported in a suitable case or frame, B. The tub is provided with a cover or lid, D, hinged to the case or frame B at the rear thereof, or to the wall-lining, and resting on the edges of the tub 25 A when down. This cover has secured to it, under an opening therein, a basin, E, which basin is of the usual or suitable form, and has the outlet *a*, to allow the waste-water to run into the tub A and thence into the waste-pipe F.

30 In addition to the regular faucets G, the tub may be provided with supplementary faucets H H, which are capable of being turned back against the edge-board *b* of the case B, as indicated in dotted lines, Fig. 1, so as to be out of the way of the cover D when the latter is turned up to allow the tub A to be used. These faucets are supplied with water by pipes *d e*, connected to the main pipes *f*, which supply the faucets G.

In some cases the basin E may be placed near the end of the cover, and the faucets G placed so that they can supply water to both the basin and the tub, as shown in Fig. 4. The faucets G in the latter case should be so 45 constructed that they may be turned out of the way of the cover D when the latter is to be raised.

It is not absolutely necessary that the hinged cover D shall entirely cover the tub A; but it 50 may extend over only a part of the tub.

When the tub is to be used the faucets are turned back and the cover D raised and secured by some suitable means in its new position.

55 My invention has the advantage that it gives a bath-tub and wash-stand at a much less cost than previously, and occupies the minimum of space in which they could be located.

Having now described my invention, what 60 I claim is—

1. The combination of a bath-tub with a hinged cover carrying a basin, and means for supplying said basin and said tub with water, substantially as described.

2. The combination of a tub, A, faucets G, hinged cover D, basin E, secured to said cover, and supplemental faucet H, substantially as described.

3. The combination of a tub, A, waste-pipe 70 F, hinged cover D, and basin E, secured to said cover, said basin having an outlet into the tub, substantially as described.

OSCAR HAMMERSTEIN.
